DOUBLING MACHINE

Leland F. Remington and Charles H. Coolidge,
Worcester, Mass., assignors to Curtis & Marble
Machine Company, Worcester, Mass., a corpora-
tion of Massachusetts

Application August 17, 1943, Serial No. 499,012

11 Claims. (Cl. 270—94)

This invention relates to a machine for dou-
bling or folding a strip of textile fabric along a
plurality of longitudinal or warp-wise lines.

It is an important object of our invention to
provide an improved machine by which either
four-ply or eight-ply fabric may be produced as
desired.

A further object is to provide a machine in
which both selvages of the fabric will be folded
to the center line in the first doubling operation,
and by which the selvages will be entirely con-
cealed in the second doubling operation.

A further feature of our invention comprises an
improved double-folding device or peak frame
by which the folding tensions at the oppo-
site selvages are balanced and lateral deviation of
the cloth is substantially avoided. Other fea-
tures relate to devices by which the machine may
be quickly and easily adapted to fold different
widths of cloth and to accurately position the
fold lines transversely in the fabric.

Our invention further relates to arrangements
and combinations of parts which will be herein-
after described and more particularly pointed out
in the appended claims.

A preferred form of the invention is shown in
the drawings, in which

Fig. 1 is a side elevation of our improved dou-
bling machine;

Fig. 2 is a perspective view of a special double
folding device or peak frame;

Fig. 3 is an enlarged front elevation of the de-
vice shown in Fig. 2;

Fig. 4 is a partial plan view, looking in the
direction of the arrow 4 in Fig. 3;

Fig. 5 is a front elevation of a single folding
device or doubling frame;

Fig. 6 is a diagrammatic view showing suc-
cessive steps in producing an eight-ply folded fabric;

Fig. 7 is a similar view showing successive steps
in producing a four-ply folded fabric; and

Fig. 8 is a sectional plan view, taken along the
line 8—8 in Fig. 3.

Referring to Fig. 6, the operations to be per-
formed in producing the eight-ply folded fabric
are as follows:

The full-width cloth C is first double-folded in
such a way that both selvage edges are folded to-
ward the center as indicated at C1. The cloth
is then similarly folded a second time, so that
the doubled outer edge portions of the cloth C1
are folded toward the center as indicated at C2.
The fabric is then subjected to a final single-
folding or doubling operation, by which the lay-
ers of fabric assume the position shown at C3,

with the selvage edges effectually concealed within
in the final folded product.

For a four-ply fabric, the operations illus-
trated in Fig. 7 are performed, with the fabric F
first double-folded to the position shown at F1
and with the selvages at the center. After this,
a simple single-folding or doubling operation
brings the layers to the position shown at F2,
in which form also the selvage edges are entirely
concealed within the final folded product.

Either the four-ply or the eight-ply product
may be made as a single continuous operation by
use of the machine shown in Fig. 1, which com-
prises a feeding or unwinding stand S, a first
double-folding device or peak frame D, a second
double-folding device or peak frame D1, a single-
folding or doubling device D2, and a cloth-dis-
posal device G.

The cloth is unwound at full width from a roll
R which rests on drums 20 and 21 connected by a
belt or chain 22 and driven by a belt or chain
23 from a drive shaft 24, the gudgeon 25 of the
roll R being guided vertically between spaced up-
rights 26.

25 The cloth as it leaves the roll R passes around
successive guide-rolls 30, 31 and 32 by which it
is conducted to the first double-folding device
or peak frame D.

As the cloth passes through the double-fold-
ing device D, it assumes the condition shown at
C1 in Fig. 6 or at F1 in Fig. 7. The doubled
cloth then passes around a guide-roll 35 and be-
tween a draft roll 36 and a pressor roll 37.

If an eight-ply fabric is to be produced, the
doubled cloth C1 then passes around a guide-roll
38 to a second double-folding device or peak
frame D1, in which it is again double-folded as
shown at C2 in Fig. 6.

The four-ply fabric C2 then passes around a
lower guide-roll 40 and between a draft roll 41
and a pressor roll 42. The fabric C2 then passes
around a guide-roll 44 to the single-folding or
doubling device D2 which delivers the eight-ply
fabric C3 to a guide-roll 45, from which it passes
45 to a roll R' resting on winding drums 50 and 51,
similar to the drums 20 and 21 previously de-
scribed.

If the final product is to be a four-ply fabric
as shown in Fig. 7, the double-folded fabric F1
delivered from the first double-folding device or
peak frame D is passed direct from the pressor
roll 37 to the guide-roll 40 and thence to the
guide-roll 44, thus by-passing the second double-
folding device or peak frame D1.

55 Our machine is thus perfectly adapted to pro-

duce either a four-ply or an eight-ply product, merely by a slight change in the threading-up of the machine.

The unwinding or feeding stand S may be of regular commercial construction, as may also the rewinding device G and the single-folding device or doubling frame D2.

The device D2 is shown in Fig. 5 as comprising an inclined folding bar 60, a horizontal bar 61, and a second oppositely inclined and forwardly displaced folding bar 62. In the doubling operation, the cloth C2 (or F2) is brought up behind the folding bar 60 and the horizontal bar 61. The left-hand portion of the cloth is then folded horizontally across the front of the inclined bar 60, while the right-hand portion is folded downward over the horizontal bar 61.

The right-hand portion then passes downward behind the second inclined bar 62, while the left-hand portion is again folded rearward and downward around the second bar 62 to bring it to reversed upright position behind the bar 62 and in front of the right-hand portion. This single-folding device or doubling frame D2 is standard practice and in itself forms no part of our present invention.

The double-folding device or peak frame D (or D1) is, however, of special construction and forms an important and novel part of our invention. The construction and operation of one of these devices is clearly shown in Figs. 2, 3 and 4.

Each double-folding device comprises a pair of inclined folding bars 70 and 71. The bar 70 is joined with a horizontal top bar 72, an inclined brace 74 and a second inclined folding bar 76. The bar 71 is joined with a horizontal top bar 73, an inclined brace 75, and a second inclined folding bar 77.

The lower ends of the inclined bars 70 and 71 are secured to threaded blocks 80 and 81. The lower ends of the brace 74 and the folding bar 76 are secured to a threaded block 82, and the lower ends of the brace 75 and the folding bar 77 are secured to a threaded block 83. The blocks 80 and 82 have right-hand threads and are mounted on portions of a two-part shaft 86 having corresponding threads, while the blocks 81 and 83 are provided with left-hand threads and are mounted on corresponding left-hand threaded portions of the shaft 86.

Forked guide blocks 88 are secured to the threaded blocks 80 to 83 respectively by connections 89, and the forked blocks 88 embrace and are guided by a fixed cross shaft 90.

At its right-hand end, the threaded shaft 86 is reduced in diameter and passes through a sleeve 92 which is threaded in a fixed frame member 93. A hand wheel 95 is mounted on the reduced outer end of the shaft 86, and a second hand wheel 96 is mounted on the sleeve 92.

By turning the hand wheel 96 and sleeve 92, the entire double-folding device or peak frame D may be shifted as a unit to the right or to the left, whereas by turning the hand wheel 95 the two folding frame members may be drawn together or moved apart to accommodate fabric of different widths.

The lower ends of the folding bars 76 and 77 are transversely slotted to permit slight adjustments of the angles of the folding bars. Slight adjustments of the folding bars 70 and 71 may be made by adjusting the fold rods 70a and 71a mounted thereon. These folding bars are all substantially at 45°, but slight variations are necessary on account of the fact that the cloth is

displaced out of its original plane during the folding operation by the thickness of the folding bars.

It will be apparent from Fig. 2 that the cloth C is first drawn up behind the folding bars 70 and 71, that each selvage portion is folded horizontally forward and toward the center, and that the middle part of the cloth is folded forward and downward around the horizontal bars 72 and 73. Each of these selvage portions is thereafter folded rearward and downward around the second folding bars 76 and 77, thus bringing the cloth to the condition shown at C1, in which the cloth is double-thickness but with both selvages turned in to the center of the folded fabric.

The turning in of both selvages as a single operation has the very important advantage previously suggested that the tensions on both edges of the fabric are equalized so that lateral deviation of the fabric is substantially eliminated. The provision of the hand wheel 96 permits adjustment during the continued operation of the machine to equalize the two folded selvages so that they will meet accurately adjacent the center line of the fabric. The provision of the second hand wheel 95, together with the expandable peak frame construction, permits the folding machine to be quickly and easily adapted to fold fabrics of substantially different widths and the by-pass arrangement permits a four-fold or an eight-fold fabric to be produced when and as desired.

Having thus described our invention and the advantages thereof, we do not wish to be limited to the details herein disclosed, otherwise than as set forth in the claims, but what we claim is:

1. In a doubling machine, a double-folding device comprising two pairs of laterally spaced and oppositely inclined folding bars, and a transverse folding member extending between the outer inclined bars at their more closely adjacent ends, and said inner inclined folding bars being disposed in separate but parallel planes.

2. In a doubling machine, a double-folding device comprising two pairs of laterally spaced and oppositely inclined folding bars, and a transverse folding member extending between the outer inclined bars at their more closely adjacent ends, and the inner inclined bars of both pairs being displaced from the plane of the outer inclined bars and of the transverse member.

3. In a doubling machine, a double-folding device comprising two pairs of laterally spaced and oppositely inclined folding bars, and a transverse folding member extending between the outer inclined bars at their more closely adjacent ends, the outer inclined bars and the transverse members being disposed in one plane and the inner inclined bars being disposed in a second plane parallel to but spaced from said first plane.

4. In a doubling machine, a double-folding device comprising two pairs of laterally spaced and oppositely inclined folding bars, and a transverse folding member extending between the outer inclined bars at their more closely adjacent ends, said transverse member comprising two adjacent portions each constituting a folding unit with one of said pairs of inclined bars, and said folding units being relatively laterally movable to adapt said double-folding device to fold different widths of sheet material.

5. The combination in a doubling machine as set forth in claim 4, in which manual means is provided to move said units simultaneously laterally but in opposite directions to adjust the folding width.

6. The combination in a doubling machine as set forth in claim 4, in which manual means is provided to move said units simultaneously laterally but in opposite directions to adjust the folding width, and in which additional manual means is provided to move said units simultaneously in the same lateral direction to shift the operative locus of the double-folding device.

7. A doubling machine comprising two associated folding units each having a pair of oppositely inclined folding bars and a transverse folding portion, the transverse portions of said two units coacting as a single folding member, and said units being laterally separable to vary the effective length of said transverse folding member for different widths of sheet material.

8. A doubling machine comprising two associated folding units each having a pair of oppositely inclined folding bars and a transverse folding portion, the transverse portions of said two units coacting as a single folding member, and a single manual means effective to change the lateral spacing of said units and the length of said transverse folding member by moving said units simultaneously laterally in opposite directions.

9. In a doubling machine, a double-folding device comprising two associated folding units each having a pair of oppositely inclined folding bars and a transverse folding portion, the transverse

portions of said two units coacting as a single folding member, manual means to change the lateral spacing of said units to vary the folding width, and additional manual means to shift the locus of said two associated units laterally to center the fold lines in the folded product.

10. In a doubling machine, a double-folding device comprising two associated folding units, each unit comprising a pair of oppositely inclined folding bars, a transverse folding portion, and a brace member in each unit connected through said transverse portion to one of the inclined bars and adjustable to vary the folding angle thereof.

15 11. A cloth doubling machine comprising a double folding device by which both selvages of a strip of cloth may be simultaneously folded toward the center, a doubling frame, a second and similar double folding device interposed between said first double folding device and said doubling frame, means to draw said strip of cloth through said double folding devices and through said doubling frame successively and continuously, and guide-rolls for said doubling machine by which 20 the cloth may be selectively guided either through or around said second double folding device.
